United States Patent Office.

EDWARD F. HOWARD, OF BOSTON, MASSACHUSETTS, ASSIGNOR TO HIMSELF AND D. W. HOWARD.

Letters Patent No. 66,963, dated July 23, 1867.

IMPROVED STEERING APPARATUS.

The Schedule referred to in these Letters Patent and making part of the same.

TO ALL WHOM IT MAY CONCERN:

Be it known that I, EDWARD F. HOWARD, of Boston, in the State of Massachusetts, have invented a new and improved Apparatus for Steering Vessels; and I do hereby declare the following to be a full and correct description of the same, reference being had to the accompanying drawings, in which—

Figure 1 is a perspective view of the apparatus complete.

Figure 2 is a vertical central transverse section through a portion of the rudder head, showing its connection with the slide by which it is operated.

Figure 3 is a central longitudinal section of the nut which operates the screws, showing its two threads cut in opposite directions.

The same part is marked by the same letter wherever it occurs.

The nature of this invention consists in a novel mode of transmitting and changing the direction of motion, which I have applied to the steering apparatus of vessels, the same consisting of a double-threaded nut, having its threads cut in opposite directions, receiving and operating two half-screws, whose threads also run in opposite directions, all as hereinafter more fully set forth.

To enable others skilled in the art to make and use my improved apparatus, I will proceed to describe its construction and operation, referring to the drawing, which is made part of this specification, and in which—

A marks the deck of the vessel; B B', two stout stanchions which support the steering-gear frame, which may be secured to them in any suitable manner. C is the rudder-head, and C' the rudder-cap, with its projecting lugs L. D D' are guide-bars, on which the slides E E' traverse. These bars are supported at either end by the heads M M'. The head M also supports the nut N, which turns on it. The slides E E' are attached to the rear ends of the half-screws S S' respectively. Each of these half-screws is of the form that would result from dividing an entire screw longitudinally through its centre. They are brought together by their flat sides, and in such a position that the thread of one runs in the opposite direction to that of the other, and both pass into and through nut N, which is provided with two threads cut in opposite directions so as to receive and operate both screws at the same time, driving them in opposite directions. The steering-wheel W is attached to the nut N. From either side of the rudder-cap C' project two arms or lugs, L, which have a parallel-sided recess between them, which receives the cubical double socket s, enclosing the ball b, at the lower end of a rod projecting downward from the side of slide E or E', forming a ball-and-socket joint.

The operation is as follows: When the wheel W is turned, one of the half-screws S S' is driven forward, and the other is driven backward, carrying with them their respective slides E E', moving on the guides D D'. These slides, by reason of their connection with the rudder-cap, through the joints b s, co-operate to turn the rudder in either direction, according to the direction in which the wheel W is turned.

It will be observed that there results from this construction a perfect equality of action of the nut upon the screws in opposite directions, so that friction from end pressure is entirely relieved. The mode herein described of transmitting and changing the direction of motion I believe to be new, and applicable to various mechanical purposes, and I contemplate its employment in those applications. This apparatus should be carefully distinguished from that form of steering-gear in which half-nuts are operated by an entire screw.

Having thus fully described my invention, what I claim, and desire to secure by Letters Patent, is—

1. A steering apparatus operated by means of two half-screws, whose threads run in opposite directions, passing through a double-threaded nut, whose threads run in opposite directions, and to which the steering-wheel is attached, substantially as described.

2. I also claim, in combination with the slides E E', operating as described, the ball b and divided socket s, arranged and operating as set forth.

3. I claim the combination of the half-screws S S', constructed and arranged as described, with the double-threaded nut N, constructed as described, for the purpose of transmitting and changing the direction of motion in the manner specified.

The above specification of my said invention signed and witnessed at Boston this 14th day of May, A. D. 1867.

EDWARD F. HOWARD.
